UNITED STATES PATENT OFFICE.

TORSTEN FORNANDER, OF ALAMEDA, CALIFORNIA.

RESILIENT WHEEL.

1,242,169.

Specification of Letters Patent.

Patented Oct. 9, 1917.

Application filed August 31, 1916. Serial No. 117,909.

To all whom it may concern:

Be it known that I, TORSTEN FORNANDER, a subject of the King of Sweden, residing at Alameda, in the county of Alameda, State 5 of California, have invented a new and useful Resilient Wheel, of which the following is a specification in such full and clear terms as will enable those skilled in the art to construct and use the same.

10 This invention relates to a resilient wheel provided with means for regulating the velocity with which the movable portion thereof moves from one position to another position, whereby different effects may be produced.

Another object of the invention is to provide means whereby the wheel will have a series of compartments separated from one another whereby the fluid used to give the 20 resilient effect will be transferred from one side of the wheel to the other as the road shocks come on the wheel.

An embodiment of the invention is shown in the drawings in which the same numeral 25 is applied to the same portion throughout the several views, but I am aware that there may be many modifications thereof without departing from the spirit of the invention.

Figure 1 is a side elevation of the wheel 30 rim, the hub and spokes not being shown, Fig. 2 is a transverse sectional view of the wheel rim, Fig. 3 is a side elevation of the rim, one flange, the movable part of the rim and the base and connected flange being cut 35 diagonally, Fig. 4 is a side elevation partly in section similar to Fig. 3, showing a slightly modified form of partition, Fig. 5 is a perspective view of one of the partition foundations used with the form of the invention shown in Fig. 4, and Fig. 6 is a perspective view of the guide block on which the partition foundation slides.

The numeral 1 indicates one of the side flanges of the rim which projects radially 45 from the base 1'. Secured to the base 1' is a ring 3 forming a flange parallel to the flange 1, bolts 13 securing the latter flange to the base 1'. Movable between the two flanges 1 and 3 is a ring 2, said ring carrying two flanges 4-4' for the tread 10. One of the flanges 4' is provided with means for detaching it from the ring 2, but this forms no part of the present invention. Bolts 11 extend through the flanges 1 and 3 and hold 50 them in tight engagement with the movable ring 2 and since said bolts pass through

holes 11' in the ring 2 much larger than said bolts the ring 2 may move with respect to the bolts as the wheel passes over the ground. 60

At intervals around the inside of the ring 2 it is provided with blocks 5 which also snugly fit against the flanges 1 and 3. The base 1' is provided with oppositely placed blocks 8 opposite to the blocks 5. Said 65 blocks have grooves therein to receive the enlarged cylindrical heads of double L-shaped partitions 6 and 7, one of said partitions having a grooved head 7' to receive the cylindrical head 6' of the partition 6. 70 The partitions 6 and 7 also snugly fit against the flanges 1 and 3.

There are a plurality of the partitions 6 and 7 around the tire whereby a plurality of 75 separate compartments are produced, and since the ring 3 is provided with a plurality of small three way cocks 12, each one of which is connected to another 180° different in position by means of the tubes 14 to 21 inclusive, any fluid or gas that may be 80 placed in the chambers formed by the flanges, ring 2 and movable partitions will be forced from one side of the wheel to the other as weight is put upon the movable ring, and the rapidity with which said 85 movement occurs will be determined by the positioning of the three way plug of the valve 12. The wheel may be filled through the three way plug by turning the plug to the proper position and turning the cap 12'. 90

The rim may be connected to any suitable wheel by means of the lugs 22. It is to be observed that owing to the shape of the partitions 6 and 7 that the ring 2, save for the pressure exerted upon it by the fluid within 95 the rim, is free to move in any direction in the plane of the flanges 1 and 3.

In Figs. 4 to 6 inclusive there is shown a slightly modified form of the invention in which 30 indicates the rim base, 31 an integral flange and 32 the flange bolted thereto by means of the bolts the same as 13. The ring is indicated at 34 and it has suitable pockets to receive radially extending partitions 35. The partitions 35 fit snugly 100 against the flanges 31 and 32 and at one end they are cylindrical as indicated at 36 and fit into grooves in blocks 37. The blocks 37 are attached to guides 38, 39, which guides are slidable in grooves 40, 41 of a block 42 105 secured to the base 30 of the rim.

The movable ring has holes therein as in-

dicated at 43, bolts 44 extending through the flanges 31, 32 to prevent them from opening with respect to the rim 30, while at the same time they permit the ring 34 to move such an amount as may be necessary. The demountable flange 32 is provided with a plurality of three way cocks 45 substantially the same as the one shown in the previous form of the invention, each cock 10 having a cap 46 to allow the insertion of fresh fluid should any leak out of the wheel, and there is a pipe 47 connected with each cock and with one 180° distance therefrom, so that when a load comes upon the movable 15 ring and any compartment is compelled to become smaller by pressure that the fluid therein will be transferred to the opposite side of the wheel, this transfer taking place continuously as the wheel rolls along. The 20 ring 34 is provided with flanges 49, 50 for securing any suitable form of tread surface thereto.

When the tire moves over the ground the ring 2 moves slightly cutting off the air 25 passage to the opposite compartment, while as soon as the extra load or bump is relieved the ring returns to its normal intermediate position, a suitable sticky and heavy lubricant being used to prevent the escape 30 of the air.

Having thus described my invention what I claim as new and desire to secure by Letters Patent of the United States, is as follows, express reservation being made of permissible modifications:

1. A resilient wheel comprising a channel rim, a movable ring in said channel, a plurality of chambers formed between the movable ring and channel, and means to convey 40 a fluid from one chamber to an oppositely placed chamber under road stresses.

2. A resilient wheel comprising a channel rim, a ring closely fitting said channel rim, movable partitions connecting the channel rim and the ring and forming a plurality 45

of compartments therewith, and a series of pipes for delivering fluid from one compartment to an oppositely placed compartment under road stresses.

3. A resilient wheel comprising a channel 50 rim, a ring closely fitting said channel rim, movable partitions connecting the rim and ring, a series of tubes adapted to deliver fluid from one of the compartments formed by the partitions, rim and ring to an oppositely positioned compartment, and means for determining the rapidity with which a fluid in said compartments will be transferred from one compartment to another under road shocks.

4. A resilient wheel comprising a channel 55 rim, a ring closely fitting said channel rim, means to prevent the flanges of the channel rim from moving away from the ring laterally, a series of movable partitions connecting the ring and channel rim and forming therewith a plurality of fluid chambers, a series of pipes adapted to transfer the fluid from one chamber to a chamber oppositely positioned, and means to regulate the rapidity 60 with which said transfer will be made under road shocks.

5. A resilient wheel comprising a channel 65 rim having lugs to connect it with a wheel center, a ring closely fitting the channel member, bolts extending through the flanges of the channel member to prevent said flanges from moving laterally away from the ring, the latter having openings therethrough larger than said bolts whereby the 70 ring may be moved with respect to the channel rim, movable partitions connecting the channel rim and ring, and means to transfer a fluid from each of the chambers thus formed to a chamber upon the opposite side 75 of the wheel under road shocks.

In testimony whereof I have hereunto set my hand this day of August A. D. 1916.

TORSTEN FORNANDER.
